UNITED STATES PATENT OFFICE.

THOR A. THORSEN, OF CHICAGO, ILLINOIS.

PLANING-MACHINE.

SPECIFICATION forming part of Letters Patent No. 397,671, dated February 12, 1889.

Application filed June 23, 1888. Serial No. 278,054. (No model.)

To all whom it may concern:

Be it known that I, THOR A. THORSEN, a subject of the King of Norway, residing at Chicago, in the county of Cook and State of Illinois, have invented a certain new and useful Improvement in Hand Planing-Machines, of which the following is a specification.

The more prominent objects of my invention are to provide a simple, compact, and efficient construction of hand planing-machine which can be readily carried from place to place within a workshop and applied at will either to a vise or to any ordinary bench, but more particularly to the former, and when so applied worked by hand, whereby the entire machine may serve as a comparatively small tool or device having a greater range of utility and capable of various uses not incident to planing-machines as constructed prior to my invention.

Further objects are to adapt the machine to a great variety of work, and to provide certain novel and improved details, all serving to increase the general utility and efficiency of the machine.

In a hand planing-machine characterized by my invention the main frame or stationary body portion of the machine is adapted for application to a vise, and the reciprocating carriage whereon a suitable tool-holder is supported is arranged so that the tool can be placed in position to act upon such work as may be placed within a vise, whereof the movable jaw preferably serves as one of the work-holding jaws, while the stationary jaw or stationary body of the vise, which is provided with the stationary jaw, serves as a holder to which the body of the hand planing-machine can be rigidly attached. A horizontal guideway for the carriage is supported upon the body portion of the machine, and the said carriage is provided with an adjustable slide to which the tool-holder is attached. The carriage is conveniently operated by a hand-lever, and at each back-stroke on the part of the carriage the slide is adjusted to a proper extent by an automatically-operating feed device. In order to permit the tool to work within a more extended field and from different standpoints, the guide for the carriage is pivotally attached to the body por-

tion of the machine and extended out therefrom, whereby it may, when desired, be swung around so that the direction of reciprocation of the carriage can be changed to any desired extent. The body portion of the machine is also provided with a laterally-arranged work-holding bracket which may upon certain occasions be employed for holding certain kinds of work, and, if desired, the said body portion of the machine can be removed from the vise and applied to an ordinary work-bench.

Certain details of construction are herein particularly described in connection with the accompanying drawings, in which—

Figure 1 represents in perspective a hand planing-machine embodying the principles of my invention and applied to a vise. Fig. 2 is a top plan view of the same with the jaws ⁷⁰ _i of the work-holding bracket I omitted for convenience of illustration. Fig. 3 represents a vertical section taken transversely through Fig. 2 on the line 3 3, the vise handle and screw being, however, shown in elevation. Fig. 4 represents in elevation the rear side of the machine shown in Fig. 1, the vise and bracket being, however, omitted. Fig. 5 represents, on a larger scale, a portion of Fig. 4, but shows a section taken through the bracket ⁸⁰ _b on the line 5 5, Fig. 2, said Fig. 5 being mainly designed to show the position of the pawl-carrying arm ⁸⁵ _e at the moment that it is about to ride upwardly along the cam or incline ⁹⁰ _e. Fig. 6 represents in perspective the reciprocating carriage. Fig. 7 represents a section taken through said carriage on the line 7 7, Fig. 6. Fig. 8 represents in plan the top of the body portion A of the machine. Fig. 9 represents a section taken on a vertical plane through the guide-plate B and the top of the body portion A of the machine. Fig. 10 represents in perspective the machine applied to a work-bench.

In said drawings, A represents the main frame or the body of the machine, and B denotes a block or plate, which is arranged upon the body A and adapted to serve as a guide for reciprocating slide of carriage C. The carriage C carries a suitably-constructed tool-holder, D, and serves to move the tool forward and back along the work. After each

forward stroke on the part of the carriage the tool is, by an automatic feed device, shifted or fed to a proper extent in a direction transversely to the movement of the carriage. To such end the tool-holder is attached to a slide, E, which latter is in turn supported upon the carriage C and arranged so that it can be adjusted by a feed-screw, e, in a direction transversely to the line of reciprocation of the carriage. As a simple construction the carriage C may consist of an oblong plate, Figs. 6 and 7, provided along its bottom side with a longitudinally-arranged dovetail channel, c, and provided across its top side with a dovetail channel, c', whereby the guide B may fit the bottom channel, c, so as to properly guide and steady the carriage, while on the other hand a rib, e', on the under side of the slide E may fit the top channel, c', of the carriage, so as to steady and direct said slide in its adjustment.

The feed-screw e is mounted in suitable bearings upon the carriage and engages the slide, whereby said slide can be adjusted by the rotation of the feed-screw. The feed-screw is at each return or back stroke of the carriage actuated by a pawl or like device, to which end the feed-screw is herein provided with a ratchet, e², which is at each back-stroke of the carriage positively engaged at a proper moment by the pawl e³. The pawl e³ may be either weighted or spring-controlled, and is arranged upon a vibratory arm, e⁴, Fig. 5, which is carried with the carriage C, and which during the back-stroke of the carriage is caused to ride along a stationary cam or incline, e⁵. The cam or incline e⁵ causes an upward swing on the part of the pawl-carrying arm, so that the pawl may positively engage the ratchet, and hence operate the same. As a means for supporting said cam or incline, it can be adjustably attached by a set-screw or screw and thumb-nut, e⁶, Fig. 5, to a bracket, b, which latter is conveniently formed by a bent plate or bar having its ends secured to the under side of the guide-plate B, as indicated by dotted lines in Fig. 2. It will be observed that the guide-plate B fits within a groove, c, in the under side of the carriage C, and that the bottom side of such portion of the guide-plate B as extends beyond the body A of the machine is exposed, whereby the bracket b can be attached to the under side of the plate B, as aforesaid. The bracket b also provides a convenient support for the fulcrum f of a hand lever, F, which is operated to reciprocate the carriage. This hand-lever is connected with the carriage by means of a pitman or connecting-rod, f', which is at one end pivotally attached to the lever and at its opposite end pivotally connected with the carriage by a universal joint, f², (see particularly Fig. 7,) whereby perfect freedom of operation is attained.

By the foregoing arrangement the reciprocating carriage, the feed device, and the device for reciprocating the carriage are all

primarily supported from a bed-plate, B, which also constitutes a guideway for supporting and guiding the carriage. This guide-plate B is adjustably secured upon the body A, so that it may be adjusted with reference to the position or character of the work. To such end the guide-plate is pivoted upon the body A by a pivot, b', about which the guide-plate can be swung when so desired. The guide-plate B can be locked in its adjustment in any suitable way—as, for example, it can be provided with screws b², arranged to engage nuts which are confined within an annular flanged or L channel, a, formed in the top of the body A, as illustrated in Figs. 8 and 9, in which way the screws can be either adjusted to tighten the nuts against the upper walls of the lower horizontal portion of the channel or adjusted so as to loosen the nuts and permit them to slide along the channel.

The main frame or body A of the machine is adapted to be placed and held within a vise, to which end it is formed with an open bottom and otherwise suitably adapted to fit upon or receive one of the jaws of a vise, as best shown in Fig. 3, wherein the body A of the machine is shown placed over the stationary jaw g of a vise, G. The opening a' in the top of said body serves to receive the upper portion of the vise-jaw g and permits the machine to be set sufficiently low down with reference to the work, which, for example, may be clamped between the movable jaw g' of the vise and one of the outer vertical sides of the body A of the machine, as in Figs. 1, 2, and 3, wherein a piece of work is shown clamped between the body A and one of the vise-jaws. In connection with such arrangement a gage, h, can be adjustably attached to the body A of the machine.

The body A is provided with one or more screws, a², whereby it can be held rigid with the stationary jaw or stationary body of the vise, so that the machine will retain its proper place when the movable jaw of the vise is adjusted for the purpose of putting in or taking out work. The said body A is at what may be termed its "front side" provided with one or more, but preferably a couple, of set-screws, a³, which, for example, can be adjusted so as to vary the angle at which the body can be held relative to a plane parallel with the vise-jaws or the work adjusted in position, as may be desired.

The tool-holder is, by preference, adjustably attached to the slide E, and to such end the slide is provided with a dovetail rib, e⁷, engaging in a dovetail groove in the back of the tool-holder, which latter can be adjusted along said rib by an adjusting-screw, E', arranged to extend along a space or recess, e⁸, in the face of the rib e⁷ and provided at either end (or both) with a suitable handle, e⁹. In connection with said screw E' any suitable pawl and ratchet or other locking device can be

employed. The feed-screw is also desirably provided with a crank or hand wheel, e^{10} , so that after the slide has been automatically adjusted in one direction to the required extent the crank or hand wheel e^{10} can be operated so as to retract the slide.

In Figs. 1 and 2 the body A is at one of its sides provided with a work-holding bracket, I, in order to enlarge the scope of action of the machine and further adapt it to various kinds of work.

The bracket I can be arranged upon the body A as a permanent fixture; but I prefer to detachably secure it to said body in any proper mechanical way, it being, for example, obvious that as one of a variety of modes for attachment the body A can be provided with holes a^5 , as in Fig. 10, for such bolts or screws as may be employed for holding the bracket in place. The jaws i are adjustably secured upon the bracket, whereby they can be set with reference to the size of the work that is to be held between them, it being observed that as a simple way of adjustably securing the jaws upon the bracket the latter can be provided with T-channels i^2 for the reception of nuts, which are understood to engage the screws i^3 . In like manner the bracket I can be provided with T-channels i^4 along one or more of its sides, so that when desired the jaws i or a similar pair of work-holding jaws can be attached to the side of the bracket.

In Fig. 10 the body A of the machine is shown secured upon an ordinary bench-top, K, in place of being applied to a vise. In said figure the work is shown held between one of the jaws i and a serrated jaw, i^5 , which latter is backed by the body A, it being observed that the serrated jaw is here employed to hold a cylindric piece of work.

It will, however, be obvious that both of the jaws i can be used when the bracket is applied as in Fig. 10, and also that either or both of said jaws i can be serrated or otherwise adapted with reference to the character of the work that is to be held between them.

Where the machine is to be rendered applicable to a bench as well as to a vise, the body A can be flanged at its base or otherwise adapted to provide bearings for bolts or clamping devices, it being understood, however, that such arrangement does not interfere with the removal of the machine from the bench and its application to a vise.

What I claim as my invention is—

1. A portable hand planing-machine having the body portion constructed hollow, with the recess a' at the top, whereby it is adapted to receive and fit upon one of the jaws of a vise, and provided with a reciprocating tool-holder arranged to permit the tool to act upon work held by the vise when said body portion is fitted upon one of the vise-jaws, substantially as described.

2. A portable hand planing-machine comprising the hollow body A, constructed to fit

upon one of the jaws of a vise and provided with screws to screw it thereto, the reciprocating carriage guided upon the hollow body, and an adjustable tool-holder supported upon the carriage, said members being combined substantially as described.

3. In a hand planing-machine, the guide-plate B, arranged upon a portable body, the reciprocating carriage arranged to work upon said guide-plate, the slide E, arranged upon and adjustable transversely to the line of movement of the carriage, a suitable tool-holder applied to said slide, and means, substantially as set forth, for securing the portable body to one of the jaws of a vise, all combined substantially as and for the purpose described.

4. In a hand planing-machine, the reciprocating carriage arranged to work upon a guide, the hand-lever applied for operating the reciprocating carriage, the slide adjustably held upon the said carriage and provided with a tool-holder, and a feed device for automatically adjusting the slide, substantially as described.

5. In a hand planing-machine, the combination, with a reciprocating carriage and adjustable tool-holder supported thereon, of the guide B, supporting the reciprocating carriage and adjustably held upon the stationary body of the machine, substantially as set forth, whereby the work may be planed from different directions or at different points, substantially as described.

6. In a hand planing-machine, the combination, with the stationary body and a reciprocating carriage arranged thereon and provided with a tool-holder, of a work-holding bracket, such as set forth, attached to said body, for the purpose described.

7. In a hand planing-machine, the combination of the hollow body portion A, provided at one side with a jaw and constructed to fit upon one of the jaws of a vise, a reciprocating tool-holder supported upon said body, and a screw arranged for holding the said body portion of the machine to the stationary jaw or body of the vise, substantially as and for the purpose described.

8. In a hand planing-machine, the combination, with the stationary body portion, substantially as set forth, of one or more screws, a^4 , arranged at one side of the said stationary body portion as a means for adjusting the same.

9. In a hand planing-machine, the combination, with the guide-plate B, of the carriage C, provided along its under side with a groove adapted to receive the guide-plate and across its upper provided with a groove, c' , wherein a portion of the slide for a tool-holder is received, substantially as described.

10. In a hand planing-machine, the combination, with the reciprocating carriage, of the slide E, provided with a tool-holder, the feed-screw supported by the carriage and engaging

the slide, and the pawl-and-ratchet device for actuating the feed-screw, and the cam or incline e^5 , for effecting the operation of the pawl, substantially as described.

5 11. In a hand planing-machine, the combination, with the guide-plate B and the reciprocating carriage C, of the bracket b , attached

to the guide-plate, and the hand-lever fulcrumed upon said bracket and connected with the carriage, substantially as described.

THOR A. THORSEN.
